P. HEELY

CARRIER FOR FIRE BRICKS

Filed April 18 1922

Fig. 1.

Fig. 2.

Inventor
Patrick Heely
By J. B. McGinn.

UNITED STATES PATENT OFFICE.

PATRICK HEELY, OF BROOKLYN, NEW YORK.

CARRIER FOR FIRE BRICKS.

Application filed April 18, 1922. Serial No. 555,501.

To all whom it may concern:

Be it known that PATRICK HEELY, citizen of the United States, residing at Brooklyn, in the county of Kings and State of New York, has invented certain new and useful Improvements in Carriers for Fire Bricks,

and means for clamping and releasing a fire-brick, said means being preferably a pair of clamps or grippers projecting from the handle and adapted to engage two of the corners of a fire-brick, one of said grippers

being adjustable with respect to the other to engage and release the fire-brick. As

This invention relates to a tool for holding, inserting into place or removing fire-bricks of water tube boilers, and its main object is to provide a tool by means of which said fire-brick may be firmly held between the jaws or grippers of the tool and readily

inserted where desired.

Another object is to make such a tool simple and easy to apply to the brick, and then the brick to its proper position in the baffle-plate and easily removed when the bricks are released by the turning of the handle.

With these and other objects in view, the improvement consists in the construction, combination and arrangement of parts, as will be hereinafter more fully described, illustrated in the accompanying drawing and pointed out in the claims. My present

design is an improvement on that form disclosed in the patent granted February 6th, 1906, No. 811,844 and it will be seen that

my present device has many advantages over the old form as will be more clearly understood by reference to said drawing

which illustrates merely an example of means for putting my improvement into practice, wherein:

Fig. 1 is a vertical longitudinal sectional view, and Fig. 2 is an elevation, showing my improvement applied thereto.

The type of boilers used in most of the power houses in this and foreign countries is known as the Babcox & Wilcox boiler. The most important feature in the construction of this type of boiler is the arrangement of the baffle walls, which deflect the flame from the fire-box and cause it to pass up and down and around the tubes, so that the greatest amount of heat from the combination will be absorbed by the water circulating through the tubes.

When water tube boilers are first constructed, or installed, the baffle-plates and bricks are inserted as the tubes are built up and are made to fit tight by the erecting engineer.

The principal elements of my tool for

holding, inserting or removing the fire-bricks of water tube boilers comprises a carrier, which is preferably as well as by necessity a handle having a pair of grippers

5 and 17, provided on its upper end with a

60 pair of clamps or grippers projecting from the handle and adapted to engage two of the corners of a fire-brick, one of said grippers

being adjustable with respect to the other to engage and release the fire-brick. As

10 This invention relates to a tool for holding, inserting into place or removing fire-bricks of water tube boilers, and its main object is to provide a tool by means of which said fire-brick may be firmly held between the jaws or grippers of the tool and readily

15 inserted where desired.

Another object is to make such a tool simple and easy to apply to the brick, and then the brick to its proper position in the baffle-plate and easily removed when the bricks are released by the turning of the handle.

With these and other objects in view, the improvement consists in the construction, combination and arrangement of parts, as will be hereinafter more fully described, the object of which

20 illustrated in the accompanying drawing and pointed out in the claims. My present

design is an improvement on that form disclosed in the patent granted February 6th, 1906, No. 811,844 and it will be seen that

25 my present device has many advantages over the old form as will be more clearly understood by reference to said drawing

which illustrates merely an example of means for putting my improvement into practice, wherein:

Fig. 1 is a vertical longitudinal sectional view, and Fig. 2 is an elevation, showing my improvement applied thereto.

The type of boilers used in most of the power houses in this and foreign countries is known as the Babcox & Wilcox boiler. The most important feature in the construction of this type of boiler is the arrangement of the baffle walls, which deflect the flame from the fire-box and cause it to pass up and down and around the tubes, so that the greatest amount of heat from the combination will be absorbed by the water circulating through the tubes.

When water tube boilers are first constructed, or installed, the baffle-plates and bricks are inserted as the tubes are built up and are made to fit tight by the erecting engineer.

The principal elements of my tool for

holding, inserting or removing the fire-bricks of water tube boilers comprises a carrier, which is preferably as well as by necessity a handle having a pair of grippers

5 and 17, provided on its upper end with a

60 pair of clamps or grippers projecting from the handle and adapted to engage two of the corners of a fire-brick, one of said grippers

being adjustable with respect to the other to engage and release the fire-brick. As

10 This invention relates to a tool for holding, inserting into place or removing fire-bricks of water tube boilers, and its main object is to provide a tool by means of which said fire-brick may be firmly held between the jaws or grippers of the tool and readily

15 inserted where desired.

Another object is to make such a tool simple and easy to apply to the brick, and then the brick to its proper position in the baffle-plate and easily removed when the bricks are released by the turning of the handle.

With these and other objects in view, the improvement consists in the construction, combination and arrangement of parts, as will be hereinafter more fully described, the object of which

20 illustrated in the accompanying drawing and pointed out in the claims. My present

design is an improvement on that form disclosed in the patent granted February 6th, 1906, No. 811,844 and it will be seen that

25 my present device has many advantages over the old form as will be more clearly understood by reference to said drawing

which illustrates merely an example of means for putting my improvement into practice, wherein:

Fig. 1 is a vertical longitudinal sectional view, and Fig. 2 is an elevation, showing my improvement applied thereto.

The type of boilers used in most of the power houses in this and foreign countries is known as the Babcox & Wilcox boiler. The most important feature in the construction of this type of boiler is the arrangement of the baffle walls, which deflect the flame from the fire-box and cause it to pass up and down and around the tubes, so that the greatest amount of heat from the combination will be absorbed by the water circulating through the tubes.

When water tube boilers are first constructed, or installed, the baffle-plates and bricks are inserted as the tubes are built up and are made to fit tight by the erecting engineer.

The principal elements of my tool for

The tool with the fire-brick is inserted edgewise by the tool illustrated herein, and the tool and brick are then turned to position, after which the tool is moved along parallel with the tubes until it is in contact with the baffle-plate, when the clamping tool of the present application may be removed. By means of this tool fire-bricks may be inserted or removed either from below or from above the bank of tubes.

By the use of my tool it is unnecessary to cut or chip any part of the brick, as its lines fit all other bricks and the curved parts fit about the adjacent pipes or tubes, by reason of the tubes being spread, permits the bricks being placed in position with as much accuracy as when they are originally placed when the baffle-wall was originally built.

The old device accomplished its work very satisfactorily in every respect, but contained many details that I have revised and incorporated herein, for instance it may be stated here that heretofore it has been customary to furnish two sets of tools of each variety for close and distant work, for instance, when working close to a wall it is impossible to use the usual long handle, so a shorter tool was provided for accomplishing the work, with my present improvements it is possible with a single tool of each variety the same work be it close to the wall or otherwise may be accomplished by the same, for instance for close work the handle as shown in Fig. 1 may be used, which is short enough to place a brick in the most closest quarters, while for placing a brick at a distance an extension handle 18 is threaded into the lower end of the handle 10, by means of this extension a fire-brick

may be placed at any point above or below the bank of tubes of the boiler.

What I claim is:—

1. A tool for holding fire-bricks comprising an outer jaw formed to receive a portion of the brick, an arm supporting the outer jaw adapted to extend along one side of the brick, a threaded boss at the inner end of said arm projecting laterally of the arm, a movable inner jaw formed as a complement to the outer jaw and adapted to engage an opposite side portion of the brick, said inner jaw being movable along said arm, a rod movably secured to the inner jaw and extending through said boss, a tubular member threaded into said boss and partially enveloping said rod, a handle member threaded upon the other end of the tubular member and being moved axially of the tubular member when rotated on the threads, said handle member having internally a shoulder, said rod having a head on its outer end adapted to engage against said shoulder, and a removable plug in the hollow handle member adjoining the shoulder for abutting against said head.

2. A tool for holding fire-bricks comprising a pair of relatively movable complementary jaws for grasping a fire-brick, a tubular member rigid with one jaw, a rod rigid with the other jaw and sliding through said tubular member, a handle threaded for rotation and axial movement upon the outer end of said tubular member, said handle having an internal shoulder, said rod having a head adapted to take against said shoulder, and an abutment in said tubular handle for striking against said head.

In testimony whereof I affix my signature.
PATRICK HEELY.
